(57) **CLAIM**

The ornamental design for a traction element for a shoe outsole, as shown and described.

DESCRIPTION

FIG. 1 is a perspective view of a traction element for a shoe outsole showing my new design;

FIG. 2 is a top plan view thereof;

FIG. 3 is a bottom plan view thereof;

FIG. 4 is a left side elevated view thereof;

FIG. 5 is a right elevated view thereof;

FIG. 6 is a front elevated view thereof; and,

FIG. 7 is a rear elevated view thereof.

1 Claim, 4 Drawing Sheets
